UNITED STATES PATENT OFFICE.

CHARLES THIDE, OF BROOKLYN, NEW YORK.

SELF-LUBRICATING AND INTERNAL-PRESSURE SPRING.

Application filed May 11, 1925. Serial No. 29,525.

This invention relates to novel and useful improvements in springs and more particularly to what I term an internal pressure and self lubricating spring wherein a plurality of superimposed leaves, when connected, are provided with a lubricating chamber so that the lubricant may flow between the respective leaves during the varying stresses and strains placed on the spring. It has been the aim and object of spring designers to construct leaf springs for motor vehicles and the like to relieve and eliminate as far as possible that quality in the metal known as fatigue. Various means have been resorted to in slotting or grooving the individual leaves and providing communicating passages therebetween so that the lubricant may flow between the crevices of said leaves. I am aware of the existence of that class of springs wherein the individual leaves are slotted at different points on each side of the central connecting bolt and to others which provide a central groove and communicating passages for the flow of oil or the lubricant. Whenever, a spring is slotted or grooved, it is weakened at some point or points between its ends. The natural result is that the spring and particularly the superimposed leaves are fractured or broken because the stresses and strains imposed on the leaves is not equally distributed throughout their areas and consequently the leaves are subject to a fracture at its weakest point. It is my object and aim to provide a self lubricating spring constructed of superimposed leaves wherein each of the leaves shall be of uniform strength throughout its area and at the same time provide for a lubricating chamber on each side of the central connecting bolt so that the lubricant may flow between the crevices of the leaves in proper proportion to the movement of the connected leaves.

In order to more fully understand and appreciate my invention, reference is had to the accompanying drawing, showing a preferred embodiment thereof, wherein,

Figure 1 is a side view.

Figure 2 is a longitudinal sectional view.

Figure 3 is a sectional view taken on the line 3—3 of Figure 2.

Figure 4 is a plan of one of the internal leaves.

Figure 5 is a sectional view showing the superimposed leaves and the lubricating chamber.

Figure 6 is a sectional end view, taken substantially on the line 6—6 of Figure 5.

Referring now to the drawings wherein like reference characters designate corresponding parts throughout all the views, 5 designates the top main leaf, which is bent or arched throughout its length and terminates in the eyes 6, 7, whereby the spring may be attached to the chassis of an automobile, for instance. There are provided a plurality of superimposed leaves 8, connected by the straps 9, 10, and a central connecting bolt 11, said leaves being of the same width but decreasing in length from the main top leaf 5 to the shortest bottom leaf 13.

Each leaf 8 is provided with a central, longitudinal groove 14, cut through the material of the leaf so that when said superimposed leaves are joined by the straps 9, 10, a lubricating chamber 15 is thus formed and provided being located on opposite sides of the central connecting bolt 11. The chambers are adapted to receive the lubricant either through such devices as alemite cups 16 or through other suitable lubricating, feeding devices whereby said chambers may function as a compression chamber or a replenishing chamber when varying stresses and strains are exerted on the spring.

It is well known in spring construction that when the superimposed leaves are slotted, they are necessarily weakened. The objection heretofore experienced in providing slots or grooves at different points in a leaf spring has been that a fracture or break occurs at a weakened point and this is due to the fact that the spring and the superimposed leaves are not of uniform strength throughout their area. My aim and object therefore is to construct a spring and particularly the leaves so that the pressure per square inch exerted on each of the leaves will be uniform as opposed to being stronger at one point than at another by reason of the slots above referred to.

In Figures 4 and 5, it will be observed that the longitudinal slots 14 in each of the leaves 8 is cut so as to provide a central thickened portion 17 of the material of the leaf at a point through which the central bolt 11 passes. This is necessary since the leaf is weakened by reason of providing the aligned apertures for the passage of the connecting bolt. The slot 14 does not terminate abruptly but on the other hand, its bottom wall slants upwardly toward the

ends 19. On each side of the slot 14 and at points located adjacent the ends of the leaves I provide what I term compensating slots 20, 21, the purpose of which is to 5 weaken the leaf at this point so that its strength will be uniform.

In order to permit a certain quantity of the lubricant to pass from one chamber 15 to the other and in and about the connecting bolt 11, each of the superimposed leaves are notched as at 22, said notches varying in their taper from the bottom leaf to the top leaf as the pressure per square inch on the leaves increases due to the length 15 of said leaves, which aids the penetrating power of the lubricant as pressure becomes greater. The spring thus formed possesses the required flexibility and resiliency with the additional advantage that the lubricant 20 may pass between the crevices of the superimposed leaves and maintain the spring in proper condition. The stresses and strains incident to the spring are taken up and compensated for and since the construction possesses uniform strength throughout its area, 25 its fracture is thus avoided. It will of course be recognized that the width or length of the leaves of the spring as well as the required thickness of the metal may be varied as circumstances and occasions may require, it being recognized that the spring must be built in proportion to the load which it is to carry.

While I have illustrated and described my invention with some degree of particularity, I realize that in practice various alterations therein may be made. I therefore reserve the right and privilege of changing the form of the details of construction or otherwise altering the arrangement 40 of the correlated parts without departing from the spirit of the invention or the scope of the appended claims.

Having thus described my invention, what I claim as new and desire to secure by 45 United States Letters Patent is:—

1. A leaf spring comprising a plurality of superimposed leaves having a central connecting element, each of said leaves, except the top leaf, being slotted longitudinally 50 throughout its length forming a lubricating chamber on each side of the connecting element, the bottom walls of said slots slanting upwardly at the ends of the leaves, and compensating slots in the ends of said 55 leaves.

2. A leaf spring comprising a plurality of

superimposed leaves having a central connecting element, each of said leaves being slotted continuously throughout its length forming a lubricating chamber on each side 60 of the connecting element, said leaves being notched adjacent the connecting element for the passage of lubricant from one chamber to the other.

3. A leaf spring comprising a plurality of superimposed leaves having a central connecting element, each of said leaves, except the top leaf, being slotted longitudinally, 65 said slots having upwardly slanting walls at the ends of the leaves and at the centers 70 thereof whereby the said leaves are thickened, a lubricating chamber formed by said slotted, connected leaves on each side of the connecting element, said chambers being in communication for the passage of the lubricant from one chamber to the other.

4. A leaf spring comprising a plurality of superimposed leaves having a central connecting element, each of said leaves, except the top leaf, being slotted longitudinally 80 throughout its length, the bottom walls of said slots slanting upwardly at the ends and at the centers of the leaves thereby providing thickened portions of the material of said leaves, compensating slots on each side 85 of the groove adjacent the ends thereof for equalizing the strength of the leaf, said connected leaves forming a lubricating chamber on each side of the central connecting element, said leaves being notched adjacent 90 said element permitting the flow of lubricant from one chamber to the other.

5. A leaf spring comprising a plurality of superimposed leaves having a central connecting bolt, each of said leaves, except the top leaf, being continuously slotted longitudinally 95 throughout its length forming a lubricating chamber on each side of the connecting bolt, the bottom walls of said slots slanting upwardly at the ends and at the centers of said leaves thereby providing thickened portions of the material of the leaves, compensating slots at the ends of the leaves equalizing the strength thereof, said leaves having notches of varying degrees from the bottom to the leaf adjacent the top leaf for the passage of lubricant from one chamber to the other in and about the central connecting bolt.

In testimony whereof I affix my signature.

CHARLES THIDE. [L.S.]
